DOORCHECK

Application filed September 27, 1927. Serial No. 222,306.

This invention relates to a modification of or improvement in a type of door check disclosed in the copending application of Henry Smith, Serial No. 708,014, filed April 21, 5 1924.

The door check disclosed in the above mentioned application consists of a rotatable drum, an abutment, and a wedge which is so positioned as to be drawn in between the 10 abutment and the drum when the drum is rotated in one direction due to the closing of the door to which the door check is attached and thus introduce a braking action which causes the door to shut very slowly 15 under the influence of the usual door closing spring which is associated with the door check.

It is sometimes desirable to have a door closed quickly for a portion of its travel and 20 then to be checked sufficiently to prevent slamming, just before the door reaches a closed position. This is particularly true of spring doors where it is desired to keep out insects.

The object of my invention is to so modify 25 the construction of the door check disclosed in the above mentioned application as to permit a door upon which such a check is mounted to close rapidly up to a certain angle and 30 then to close slowly under the influence of the braking action of the check in the same manner that it would if controlled by hydraulic or pneumatic check.

This and other objects and advantages and 35 the manner of accomplishing them will be more clearly understood by reference to the following description and the accompanying drawings.

In the drawings, Fig. 1 illustrates a plan 40 view of a door check constructed in accordance with my invention.

Fig. 2 illustrates the door check as it is applied to a door.

Fig. 3 is a sectional view of the door check 45 taken along lines 3—3 of Fig. 1.

Fig. 4 is a bottom plan view of a portion of the door check showing the braking mechanism.

Fig. 5 is a view of a modified form of abut- 50 ment and wedge which may be used in place

of the abutment and wedge shown in Fig. 4.

Fig. 6 is a detail view in elevation of the friction wedge and guides shown in Figs. 3 and 4.

The door check consists of a housing 1 having a cover 2, which housing encloses a shaft 3 rotatably supported within the housing by bearings 4 and 5. Around shaft 3 is positioned a collar 6 which cooperates with the bearing 4 and a sleeve 7 which cooperates 55 with a bearing 5. Shaft 3 is keyed to the sleeve 6 but is freely rotatable within the sleeve 7. Sleeve 7 is provided at its outside end with a flange 8 which has a series of 60 perforations 9 within which projections 10 of a key member 11, slidably mounted on the shaft 3, are positioned. The key 11 is prevented from rotation relative to the shaft 3 due to the hexagonal shape of the shaft and the corresponding hexagonal perforation in 65 the key, within which the shaft is positioned. The key 11 is freely slidable longitudinally 70 of the shaft and hence in order to vary the angular position of the shaft relative to the sleeve 7 it is necessary merely to withdraw 75 the key 11 sufficiently so that the projections 10 disengage from the perforations 9 of the flange 8, then rotate the shaft 3 to the desired position and thrust the key back into its former position in such manner that the 80 projections again engage with the perforations in the flange. This key adjustment arrangement forms part of the subject matter of the copending application of W. F. Hendry, filed September 21, 1927, Serial No. 85 221,001. Secured to the shaft within the housing is a brake drum 12 which cooperates with an elongated friction wedge 13 positioned between the periphery of the brake 90 drum and an abutment 14, which abutment has integral therewith an arm 15 secured to the housing cover 2 by rivets, or other suitable means. For adjusting the position of the abutment relative to the periphery of the drum there is provided a thumb screw 95 16 which is threaded through the walls of the housing 1 and the cover 2. In order to draw the wedge in between the abutment 14 and the surface of the brake drum 12 to its proper operative position, a spring 17 is pro-

vided. This spring is attached to the end of the wedge and to the cover plate 2 in any suitable manner and is tensioned just sufficiently to keep the wedge in contact with the surface of the brake drum. In order to prevent too great a movement of the friction wedge the width of the wedge is reduced at a point intermediate its ends, as shown at 18 and is positioned between a pair of guides 19 integral with the abutment 14. By this arrangement when the wedge is moved in one direction too far the enlarged portion 20 thereof will engage with the abutment, and in the other direction the enlarged portion 21 will engage with the abutment, thus maintaining the wedge at all times in its proper operating position and therefore preventing the wedge from jamming too tightly between the periphery of the brake drum 12 and the abutment 14 during the operation of the check. Surrounding the sleeve 7 and attached at one end thereto is a spiral spring 22 which spring is attached at its outer end to the housing 1 in any suitable manner, for example by means of a hook portion in the end of the spring projecting through and engaging with the wall of the housing 1, as indicated at 23. In order to prevent oil which may be used to lubricate the spring 21 from coming into contact with the braking surface of the drum 12, a washer 24 is positioned between the spring and the drum. The sleeve 7 is maintained in its proper position by means of a spring clip 25 positioned around the end of the sleeve and engaging with the washer 24. The drum 12 has a portion of constant radius, as indicated at A, a portion of reduced radius, as indicated at B, and a third portion of gradually reduced radius, as indicated at C. These three different portions of the brake drum 12, which may be arranged in any desired relative position, co-operate with the friction wedge 13 to give the door check its desired operating characteristics, in a manner more fully to be described hereinafter. When positioned as illustrated in Fig. 4 the function of portion C is to permit free swinging of the door during its initial closing movement, then gradually to retard its movement; of portion A, is uniformly to retard the intermediate closing movement of the door; and of portion B, to release the retarding force and permit free closing of the door just prior to its latching position. In order to insure the best action of wedge 13, the wedge is provided with a facing 26 of leather or brake lining material, which may be secured to the wedge in any suitable manner, for example, by riveting.

As illustrated in Fig. 2 the door check is secured to a door 27 by means of a bracket 28 attached to the housing 1 of the door check. Attached to the jamb of the door is a hinge member 29 to which is threaded a rod 30 engaging with a lever arm 31 keyed to the end of

the shaft 3, so that through the action of the rod 30 and the lever arm 31 when the door is opened the shaft 3 is rotated carrying with it the brake drum 12. The shaft 3 extends out of the casing at both ends so that the arm 31 can be attached to either end of the shaft, according to whether the door swings right handedly or left handedly.

When the door is opened from its closed position the drum 12 is rotated by the shaft 3, in a counter-clockwise direction, as viewed in Fig. 4, until the point 32 of the drum assumes a position adjacent to the small end of the wedge 13. When the door is released, the spring 22 which has been wound up by the opening of the door causes the shaft 3 to be rotated and the door to be closed through the cooperation of the lever arm 31 and the rod 30. As the door starts to close the drum 12 is rotated in a clockwise direction, as viewed in Fig. 4. As the portion C of the periphery of the drum, which is now adjacent to the friction wedge 13, is of reduced radius, the wedge will not at first exert pressure on the brake drum surface. However, as the door closes further the drum 12 will continue to be rotated in a clockwise direction which will cause the portion of the brake drum of increased radius to be brought into contact with the friction wedge 13. This will be brought about gradually and will result in the contact pressure between the wedge 13 and the drum being gradually increased and as a result thereof the rotation of the drum 12 and the closing of the door will gradually be retarded so that by the time the portion A of the brake drum has reached the active section of the friction wedge the door will receive its greatest retarding effect, as the pressure between the surface of the brake drum and the wedge will then be a maximum. The door will then close slowly for a period of its travel until the portion B comes adjacent to the friction wedge. As this portion B is of reduced radius, the pressure between the brake drum and the wedge will immediately be reduced and hence the door will be able to close freely under the action of the spring 22. When the door is opened again the drum 12 will be rotated from its closed position, as shown in Fig. 4 in a counter-clockwise direction, and will, due to the friction between the brake drum and the wedge 13, cause the wedge to be thrust outwardly from between the abutment 14 and the surface of the drum 12 in such manner as to reduce any braking effect to a minimum. The check is then again ready to repeat its action, as above described. It will be noted that the portion C of the periphery of the brake drum 12 is of very gradually reduced radius so that as the door closes the pressure of the drum against the friction wedge 13, and the corresponding braking action, will be very gradually increased in order not to put too severe a strain on the working mechanism.

and to preclude any danger of jamming the wedge so tightly between the brake drum and the abutment as to stop the movement of the door entirely. It should also be noted that by making the curvature of the brake drum at the portion C change very gradually that the point of contact between the brake drum periphery and the facing of the friction wedge 13 will be made relatively large and hence the facing of the wedge will be subjected to less wear than it would be if the curvature of the portion C were made very sharp, in which case the facing of the friction wedge would be rubbed by a relatively sharp hump of small bearing area. This question of a gradual curvature is not of so much importance at the portion B of the brake drum for the reason that the angular velocity of the brake drum when the portion B approaches the friction wedge is very much less than when the portion C strikes the wedge. In order to prevent the facing 26 from slipping relative to the wedge 13 under the heavy strain caused by the portion C of the drum hitting the wedge facing 25 when the drum is traveling at a high angular velocity, precaution should be taken to secure the facing tightly to the wedge. This may be done by placing rivets at short intervals or by corrugating or furrowing the surface of the wedge 13 at this point of contact with the facing, as shown at Fig. 5. For this same reason too thick a facing should not be applied to the wedge as a relatively thick facing might be jammed out of shape by the impact of the portion C of the brake drum in such manner as to cause the thickness of the facing to be increased at a point just in front of the point of contact of the drum with the facing and rotation of the drum to be stopped. In order to overcome any tendency toward jamming or sliding of the facing on the wedge, it might be advisable in some cases to divide the facing of the wedge into a plurality of spaced sections each securely fastened to the wedge face. In some cases it may be found advisable in order to insure positive and efficient working of the door check to utilize the modified form of abutment shown in Fig. 5, which is so constructed as to give a pivotal bearing 45 surface for the friction wedge. With this type of abutment the wedge is permitted to align itself relatively to the face of the brake drum 12 so that the area of contact between the facing of the friction wedge and the brake drum periphery will be made as large as possible and therefore the pressure per unit area made as small as possible. With this type of abutment the portion C of the brake drum upon striking the surface of the wedge will cause the wedge to rock about its pivotal contact with the abutment and assume a position substantially tangential to the surface of the wedge at that point. As the portion C of the drum travels past the face of the wedge 55 the wedge will rock about the abutment and accommodate itself to the varying curvatures of the drum so that very little pressure will be applied to the wedge until the point of increasing radius of the drum has passed by the pivotal point of the abutment. Hence, 70 the facing at the heel of the wedge will not receive as hard wear as it would if the wedge were supported throughout its entire length, in which case, as the wedge would not be free to rock around the abutment, a certain point 75 of the face would receive the full shock pressure of the point of increased radius of the brake drum as the drum was rotated under the high initial velocity of the swinging door. 80

The tension of the door check spring may be adjusted for different working conditions by withdrawing the key 11 from engagement with the flange 8 of sleeve 7, rotating the sleeve to give the spring the proper tension 85 and then replacing the key in its proper position. Likewise the effective length of the rod 30 can be varied by screwing the rod in or out of the hinge member 29. 90

It will be seen that the above disclosed friction check, which comprises a minimum of working parts, can be adjusted to act in exactly the same manner that a hydraulic or pneumatic check does, and without the fluids, cylinders, pistons and valves used in such 95 devices. 100

It will be obvious to those skilled in the art that the invention is capable of a wide variety of modifications and adaptations and that the present disclosure is intended merely to illustrate its nature without limiting its scope, which is defined in the following claims. 105

What I claim is:

1. In a door check, a rotatable drum and an abutment, a friction wedge positioned between said drum and said abutment, said drum having a plurality of mutilations thereon for enabling the major portion of the door closing movement to be effected rapidly and the final closing movement relatively slowly. 110
2. A door check comprising a brake surface adapted to be moved responsive to the closing of a door, a friction surface coacting with said brake surface to retard the closing of the door, said brake surface being mutilated at a plurality of places in order to reduce the coaction between said surfaces in such a manner that the major portion of the door closing movement is effected rapidly and the final closing movement relatively slowly. 115
3. A door check comprising a drum, means to rotate the drum responsive to the closing of a door to which the check is applied, a friction brake surface, coacting with said drum for retarding the closing of the door, and a plurality of mutilations on said drum 120
- 65

for reducing the said retarding effect in a predetermined manner.

4. In a door check, a drum, means for rotating the drum responsive to the closing of a door to which the check is applied and a friction brake surface positioned to press against the said drum and retard the closing of the door, said drum being shaped to reduce the pressure of the brake surface against the drum when the door is near its open position, and to increase the pressure as the door nears its closed position.

5. In a door check, a drum, means for rotating the drum responsive to the swinging of a door to which the check is applied and a friction brake surface positioned to press against the said drum and retard the closing of the door, said drum being shaped to reduce the pressure of the brake surface against the drum during the greater portion of the closing movement of the door, then gradually to increase the pressure as the door approaches a closed position.

6. In a door check, a drum, means for rotating the drum responsive to the swinging of a door to which the check is applied and a friction brake surface positioned to press against the said drum and retard the closing of the door, said drum being shaped to reduce the pressure of the brake surface against the drum when the door is near its open position, then gradually to increase the pressure as the door approaches a closed position, and finally quickly to reduce the pressure just before the door starts to latch.

7. In a door check, a brake drum and a cooperating friction wedge, said drum having a large constant radius portion having at both sides a portion of reduced radius, on one side the radius of said drum being gradually reduced from the portion of constant radius to the portion of reduced radius.

8. In a door check, a brake drum rotatably responsive to the closing of a door, an abutment, a wedge positioned between the abutment and the drum, means for limiting the movement of the wedge, said drum having a portion of reduced radius so placed as to coincide with the greater portion of the wedge surface when the door is in a position just about to shut and having another portion of reduced radius so placed to coincide with the greater portion of the wedge surface at another position of the door.

9. In a door check, a brake drum and a friction member for pressing against the surface of said drum, said drum having a portion of gradually reduced radius of curvature so located as to lie substantially in registry with the greater portion of said friction member when the brake drum occupies a position corresponding to the open position of a door.

10. In a door check, a brake drum and a friction wedge for pressing against the surface of said drum, said drum having a portion

of reduced radius located in the neighborhood of the portion of the drum adjacent to said wedge, when the drum is in a position corresponding to the open position of a door.

11. In a door check, a brake drum, an abutment and a friction member positioned between said abutment and said drum, said drum having a portion of gradually and uniformly reduced radius of curvature so located as to be substantially in registry with said friction member when the brake drum occupies a position corresponding to the open position of a door and said abutment having a projection against which said friction member thrusts itself, and around which said friction member is adapted to rock.

12. In a door check, a rotatable brake drum, an abutment and a friction member positioned between said abutment and said drum, said drum having a portion of reduced radius so located as to be substantially in registry with said friction wedge when the brake drum occupies a position corresponding to the closed position of the door and a second portion of reduced radius at another point on the drum.

13. In a door check, a rotatable brake drum and a friction wedge for pressing against the surface of said drum, said drum having a portion of gradually reduced radius of curvature so located as to be substantially in registry with said friction wedge when the brake drum occupies a position corresponding to the open position of a door, and having a second portion of reduced radius so located as to be substantially under said friction wedge when the brake drum occupies a position corresponding to the closed position of a door.

In testimony whereof, I have signed my name to this specification this 22nd day of September, 1927.

EDWARD D. PHINNEY.
